UNITED STATES PATENT OFFICE.

OSCAR ROESEN, OF NEW YORK, N. Y., ASSIGNOR TO ROBERT HOE, THÉODORE H. MEAD, AND CHARLES W. CARPENTER, OF SAME PLACE.

PRINTING-PRESS.

SPECIFICATION forming part of Letters Patent No. 629,968, dated August 1, 1899.

Application filed April 27, 1898. Serial No. 678,947. (No model.)

To all whom it may concern:

Be it known that I, OSCAR ROESEN, a citizen of the United States, residing at New York, county of New York, and State of New York, have invented certain new and useful Improvements in Printing-Presses, fully described and represented in the following specification and the accompanying drawings, forming a part of the same.

10 This invention relates to printing-presses, and has for its especial object to provide means in perfecting presses for holding the sheet to the impression-cylinder without the liability of soiling the same by offset ink. It is usual 15 for the sheet to be held to the impression-cylinder by grippers, which press the sheet upon the tympan. After the tympan becomes slightly soiled this pressure of the sheet under the grippers is likely to produce an offset 20 upon the sheet. In work where there is no trimming this offset is a serious injury to the product, and where paper wide enough to trim is used considerable expense is entailed. In order to overcome this difficulty, I have de- 25 vised my present invention, which consists in providing a gripper bearing-piece so placed that the grippers may close upon it in grasping the sheet, and thereby hold the sheet in proper position to receive the impression and at the 30 same time so that it shall not interfere with the free shifting movement of the tympan to present fresh tympan-surfaces. To this end one form of my invention consists in mounting the bearing-piece movably, so that when 35 the grippers are resting upon it it shall rest against the edge of the cylinder-shell which supports the tympan or against the tympan itself, and when the grippers are in their retracted position and the tympan is to be 40 shifted the bearing-piece shall be moved back from the tympan, so as not to interfere with the movement of the latter.

In the drawings annexed, Figure 1 is a vertical sectional elevation of the part of an impression-cylinder embodying my invention, in which the bearing-piece and grippers are in the position in which the sheet is held by them upon the cylinder. Fig. 2 is a similar view showing the position of the parts in which 50 the grippers are open and the bearing-piece

is withdrawn from the tympan. Fig. 3 is a view of the same mechanism from above, the point of view being shown by the arrow 3 in Fig. 1. Fig. 4 is a similar view on a reduced scale.

55 A is the shell of an impression-cylinder upon which is the blanket B, held by the blanket-grippers B'. The sheet-grippers are shown at C, mounted upon the gripper-rod D. The bearing-piece for the sheet-grippers is shown 60 at E mounted upon arms F, pivoted upon the shaft D, and connected with a swinging spring-rod G. Fast upon the gripper-shaft are a series of lugs H, and connected with the arms F are a series of lugs I, so placed that the lugs 65 H meet the lugs I when the grippers are almost fully opened and cause the arms F to swing against the pressure of the spring-rod G until the bearing-piece E takes the position shown in Fig. 2. In this position the tympan is free 70 and may be shifted as desired.

When it is wished to withdraw the bearing-piece E farther from the edge of the cylinder-shell in order to afford more room for access to the interior of the cylinder, the bearing-piece may be thrown back to the position shown in broken lines in Fig. 2, in which case 75 the spring-rod G swings to the position shown in broken lines and holds the bearing-piece in its position of farthest withdrawal until 80 sufficient force is applied to the bearing-piece to shift it back to the position shown in Fig. 2.

The tympan passes over the tension-rols K K' to a tympan-carrying roll. (Not shown.) Any of the well-known tympan-shifting de- 85 vices may be employed for shifting the tympan—such, for instance, as that shown in the patent to Crowell, No. 596,025, dated December 21, 1897.

90 What I claim is—

1. The combination of an impression-cylinder, tympan-shifting mechanism, sheet-grippers, and a movable bearing-piece therefor normally resting against the tympan, said bearing-piece being so mounted as to withdraw at the proper time so that it shall not interfere with the movement of the tympan, substantially as set forth. 95

2. The combination with an impression-cylinder, of a tympan-shifting mechanism, a set 100

of grippers, a bearing-piece therefor normally resting against the tympan, a rod upon which the bearing-piece is mounted, and means for giving the bearing-piece an axial movement 5 with respect to the rod in order to permit the operation of the tympan-shifting mechanism, substantially as described.

3. The combination with an impression-cylinder, of a tympan-shifting mechanism, a set 10 of grippers, a movable bearing-piece therefor, and means brought into operation by the movement of the grippers, whereby the movement of the bearing-piece is effected, substantially as described.

15 4. The combination with an impression-cylinder, of a set of grippers, a rod upon which the grippers are mounted, and a bearing-piece for the grippers loosely mounted on said rod, substantially as described.

20 5. The combination with an impression-cylinder, of a set of grippers, a gripper-carrying rod, a bearing-piece for the grippers loosely mounted on said rod, and means operating to hold the bearing-piece in one position of the 25 parts against the edge of the gripper-opening and in another position away from the edge of said opening, substantially as described.

6. The combination with an impression-cylinder, of a set of grippers, a movable bearing-piece for the grippers, and means operating 30 to hold said bearing-piece in one position against the edge of the gripper-opening and in another position away from said edge, substantially as described.

35 7. The combination with an impression-cylinder, of a set of grippers, a movable bearing-piece therefor, and means brought into oper-

ation by the movement of the grippers, whereby the movement of the bearing-piece is effected, substantially as described. 40

8. The combination with an impression-cylinder, of a tympan-shifting mechanism, a set 45 of grippers, a gripper-carrying rod, a movable bearing-piece for the grippers loosely mounted on the rod, means for holding the bearing-piece normally against the edge of the gripper-opening, and means carried by the gripper-carrying rod for moving the bearing-piece when the grippers are opened, substantially 50 as described.

9. The combination with an impression-cylinder, of a tympan-shifting mechanism, a set 55 of grippers, a gripper-carrying rod, a bearing-piece for the grippers loosely mounted on the rod, a spring operating to hold the bearing-piece against the edge of the gripper-opening in one position of the parts and away from said edge in another position of the parts, and means carried by the gripper-carrying rod for 60 moving the bearing-piece against the stress of the spring when the grippers are opened, substantially as described.

10. The combination of bearing-piece E mounted on arms pivoted to the gripper-rod 65 with lugs H and I, substantially as set forth.

11. The combination of bearing-piece E, arms F, spring-rod G, lugs H and I, substantially as set forth.

In testimony whereof I have hereunto set 70 my hand in the presence of two subscribing witnesses.

OSCAR ROESEN.
